UNITED STATES PATENT OFFICE.

ARTHUR L. SMITH, OF MELROSE, MASSACHUSETTS, ASSIGNOR TO THE A. L. SMITH IRON WORKS, OF CHELSEA, MASSACHUSETTS, A CORPORATION OF MASSACHUSETTS.

CLINKER TONGS.

Application filed February 13, 1922, Serial No. 536,332.

To all whom it may concern:

Be it known that I, ARTHUR L. SMITH, a citizen of the United States of America, and resident of Melrose, in the county of 5 Middlesex and State of Massachusetts, have invented new and useful Improvements in Clinker Tongs, of which the following is a specification.

This invention relates to fire tongs and 10 more particularly to devices primarily intended for removing lumps of slate, clinkers and other incombustible material from furnaces.

In the operation of domestic heaters and 15 furnaces it frequently happens, due in part perhaps to the low grade of coal at present available, that lumps of slate or clinkers accumulate in the fire box to such an extent as seriously to interfere with the proper 20 combustion of fresh fuel while at the same time restricting the capacity of the fire box to a material extent. These lumps or clinkers are often of a size such that it is 25 impossible to pass them between the grate bars, either by shaking the latter or by the use of a poker or slice bar, and consequently 30 the only feasible mode of removing them is by drawing them out through the fire door. For this purpose the ordinary fire 35 tongs are inadequate by reason of their small size and insufficient length, while tongs such as are employed for metallurgical purposes are cumbersome, heavy and usually unavailable to the ordinary householder or 40 janitor.

The object of the present invention is accordingly to provide fire tongs peculiarly adapted for removing lumps of incombustible material from the fire boxes of domestic 45 heaters or furnaces, such tongs being of simple, light and durable character, easy to construct and which may be sold at a reasonable price.

In the accompanying drawings, there is 50 illustrated by way of example one embodiment of means well adapted for attaining the above object, and in which drawings,—

Figure 1 is a side elevation of the tongs device constructed in accordance with the 55 present invention;

Figure 2 is a vertical cross section to larger scale on the line A—B of Fig. 1;

Figure 3 is a fragmentary horizontal cross section to large scale on the line C—D of 55 Fig. 1; and

Figure 4 is a cross section to large scale on the line E—F of Fig. 1.

Referring to the drawings, the tongs device is illustrated as comprising a bar 1 herein disclosed as of channel iron and 60 comprising the laterally extending flanges 2, 3, which define the channel 4. Adjacent to one of its ends this bar is bent or twisted as indicated at 5 to provide the handle element 6 which projects substantially at right 65 angles to the main body of the bar and in the plane defined by the back or flat surface of such bar. As indicated in Fig. 3, the channel 7 in the handle element 6 is directed toward the opposite end of the bar 70

1. Adjacent to such opposite end the bar is twisted as indicated at 8 to provide a jaw portion 9 extending substantially in alignment with the main body of the bar and having its channel face 11 turned at substantially 90° to the channel face of the main body of the bar. This jaw member 9 is provided at 10 with a curved extremity. 75

A lever 12 of channel cross section is pivotally secured at the point 13 to the bar 1, 80 the lever and the bar being arranged in back to back relation with their flat, unchanneled surfaces in contact. This lever is twisted or bent at the point 14 to provide a movable jaw member 15, the channelled 85 face 17 of which is arranged in opposing relation to the channel surface 11 of the jaw 9. This jaw 15 is also curved at its outer extremity as shown at 16.

The opposite arm 18 of the lever is provided with an opening 19 to which is secured the end of a flexible actuating member 20, such member being of wire or other suitable material. This member is suitably guided in openings in a pair of bracket 95 members 21, 22, secured to the flat face of the bar 1 by means of rivets 23. These brackets extend upwardly from the flange 2 of the bars, lying substantially in the plane of the handle element 6. At its free extremity the connecting member 20 is bent to provide a hand grip 24 having the element 25 adapted to be grasped by the hand of the user. This element 25 preferably lies in the vertical plane of the handle element 100 6 and closely adjacent thereto.

In the use of the device the operator introduces the open jaws into the firebox and by manipulation of the hand grip 24 causes the movable jaw 15 to approach the fixed 110

jaw 9 whereby the clinker or other material to be removed is gripped between the opposing channel faces of the jaws, the curved ends 10 and 16 of which facilitate such operation. The jaws may be manipulated by the right hand of the operator, which may simultaneously grasp the handle element 6 and the element 25 of the hand grip, the left hand being free to grasp the bar 1 and 10 direct the jaws toward the material to be removed. When the jaws are closed, the element 25 may lie within the channel 7 of the hand grip so as to permit holding the jaws in closed position with the expenditure of but little effort on the part of the user.

The inherent resiliency of the connecting element 20 may be such as to permit a firm grip to be obtained upon the material while the operator holds both the member 6 and 20 the member 25 within the grasp of his hand, but if further resiliency be desired it is contemplated that spring means may be introduced within the length of the connecting element 20 whereby to secure such added 25 elasticity in a longitudinal direction as may be required.

While as herein illustrated, channel iron is preferably employed in forming the tongs device, it is contemplated that material of 30 any desired section may be substituted therefor, and in its broader aspects it is to be understood that the invention is not to be limited to the employment of such channel iron in forming any or all of its structural elements.

What I claim and desire to secure by Letters Patent of the United States is:

A clinker tongs device comprising a channel bar having an angularly disposed end portion constituting a handle element, a jaw 40 member integral with said bar at the opposite end thereof, said jaw member being substantially in alinement with the bar and having its channeled side disposed substantially at ninety degrees to that of the bar, 45 such channeled side of the bar constituting the gripping face of the jaw member, a lever of channeled cross section pivotally secured in back to back relation to the bar, said lever having one end thereof so disposed as to 50 present its channeled face opposite that of the jaw member whereby to constitute a co-operable, movable jaw member, brackets secured to the flat, rear face of the bar, and projecting in the vertical plane of the handle element, a flexible connection secured to the other end of the lever and passing through guide openings in the several brackets, said connection having a hand grip at its free end having the hand engaging portion thereof disposed in the plane of the handle element and constructed and arranged to be grasped simultaneously with the handle element by the hand of the user and to be drawn toward the channel of such 55 element.

Signed by me at Boston, Massachusetts, this 3rd day of February, 1922.

ARTHUR L. SMITH.
